INFANT'S FOLDABLE BATHTUB TABLE

Filed May 19, 1930

INVENTOR,
Herbert A. Masters
BY
J. E. Trabucco
ATTORNEY.

UNITED STATES PATENT OFFICE

HERBERT A. MASTERS, OF SAN FRANCISCO, CALIFORNIA

INFANT'S FOLDABLE BATHTUB TABLE

Application filed May 19, 1930. Serial No. 453,450.

This invention relates to an improved infant's tray adapted for use with bath tubs.

An object of my invention is to provide an improved tray or table adapted for use with bath-tubs to support an infant before or after it is bathed.

Another object of my invention is to provide an improved table or tray having a plurality of foldable legs which are adapted to support the table in a convenient position above a bath tub or above the surface of the ground or floor.

A further object of my invention is to provide a foldable table or tray for use in supporting infants, having suitable means embodied therein for mounting a protective canopy over the same.

A still further object of my invention is to provide an improved tray or table which may be readily folded into compact form.

Other objects more or less apparent will present themselves or will be specifically pointed out in the description to follow.

In the accompanying drawings:

25 Figure 1 is a perspective view of an infant's tray or table constructed in accordance with my invention, showing the same supported above a bath tub in a normal operative position;

30 Figure 2 is a sectional view taken on the line 2—2 of Figure 1; and

Figure 3 is a perspective view of the table or tray, showing a plurality of upright members mounted thereon in a position adapted 35 to support a protective canopy.

The frame of my improved table or tray consists of a pair of rigid side members 1 joined by a pair of hinges 2 to a pair of similarly constructed side members 3, and a pair 40 of rigid cross members 4 secured to the pairs of side members as by screws, angle irons or other suitable means. Extending over the side edges of the side and cross members and suitably affixed thereto as by tacks, is a sheet 45 5 of duck, canvas or other strong fabric, which, when the frame is opened, constitutes a flat and firm tray or table on which an infant may be supported. Suitably secured as by screws to the side members 1 at points adjacent the hinges 2, are cooperating

lock or catch members 6 of any well known make, which when in engaged positions, maintain the frame in an unfolded position with the sheet 5 flatly disposed. The catch members 6 are preferably of the spring pressed 55 type, and the cooperating parts thereof may be readily disengaged from each other to permit the frame and sheet to be folded into a compact form.

Pivottally attached to the cross members 60 4 as by hinges 7, are two pair of legs 8, each of the said pairs being secured to a cross bar 9, as by a screw or nail, which extends beyond the legs for a certain distance. One of the legs of each pair is provided at its outwardly disposed side with a projecting pin or screw 10 which is adapted to pass through a hole located in a spring clip 11 secured to a cross member 4. When the pins 10 of the legs 8 are located in the holes of the clips 11, 70 the legs are maintained in upright positions. To permit the folding of the legs to a position where they are located partly between the side members 1 and 2, the clips are manually pressed in outward directions to free the 75 said clips from the pins 10.

Detachably mounted between the curved ends of brackets 12 which are secured to the inner sides of the cross members 4, are a number of rods 13. Ends of the rods are adapted 80 to be inserted into holes 14 located in the top side of the frame at points adjacent its corners. The rods when positioned in the holes in the frame are vertically disposed to permit the proper supporting of a suitable canopy 85 or covering which may be draped over the same for protection purposes.

As shown in Figure 1, the table or tray when in an unfolded position, may be supported above a bath-tub 14 with the cross-bars 9 resting on the upper edge of the tub and the legs 8 in contact with the inner surface of the same. The legs serve as means for preventing the normal displacement of the table or tray, while the cross-bars serve 90 to properly support the table or tray in a desirable and convenient position above the tub.

The legs 8 may be positioned closer to or 100 farther from each other so they may be prop-

erly accommodated within the side edges of bath tubs of different sizes, by attaching the hinges 7 at different points to the cross members 4. The frame and sheet 5 may be either 5 elevated or lowered to the desired position by attaching the cross-bars 9 to the legs at different points thereon.

The tray or table when not used with bath-tubs may be placed on a floor or other supporting surface with the ends of the legs resting on the said surface. The sheet 5, when 10 the frame is in an unfolded position, serves to properly support a child placed thereon.

Having described my invention what 15 claim is:

1. In a bath-tub table, a frame, a sheet extending over the frame, legs pivotally attached to the frame, locking means for normally maintaining the legs in substantially 20 rigid positions with reference to the frame, and cross bars secured to the legs at points thereon between the frame and the ends of the legs, the said cross bars being adapted to rest on the edges of a bath tub to maintain 25 the frame and the sheet above the said tub.

2. In a bath-tub table, a frame, a sheet extending over and attached to the frame, legs pivotally attached to the frame, the said legs being so separated from each other that they 30 are adapted to contact with the inner surface of an ordinary bath-tub, and cross bars attached to the legs at points thereon between the frame and the ends of the legs, the said cross-bars being adapted to rest on the top 35 edges of the bath tub to maintain the frame and the sheet above the said tub.

In testimony whereof I have affixed my signature.

HERBERT A. MASTERS.
